4 Claims. (Cl. 200—33)

The present invention relates to the control of photographic apparatus. The invention is more especially, but not exclusively, concerned with apparatus for use in aerial photography.

The object of the present invention is to provide a control of this type which is better adapted to meet the requirements of practice than those used up to the present time.

According to an essential feature of the present invention, concerning automatically operated photographic apparatus worked by electrical impulses, I make use, for producing these impulses in the desired circuit, of a mechanism including the following elements:

On the one hand, a movable member adapted to move along a driving element, such for instance as a screw, against the action of elastic means;

On the other hand, means, preferably adjustable in position, for uncoupling said movable member and said driving element, when said movable element comes into contact with said last mentioned means;

And, finally, means, operative by the movable member, in the course of its return movement, for temporarily closing the above mentioned circuit, after which said movable member comes back into cooperating engagement with the driving element for repeating the same cycle of operations.

Other features of the present invention will result from the following detailed description of some specific embodiments thereof.

Preferred embodiments of the present invention will be hereinafter described, with reference to the accompanying drawings, given merely by way of example and in which:

Fig. 1 is an elevational view, with the casing cut off, of a mechanism made according to the present invention for producing electrical impulses intended to operate an automatic photographic apparatus;

Fig. 2 is a horizontal sectional view on the line II—II of Fig. 1;

Fig. 3 is a vertical sectional view on the line III—III of Fig. 1;

Fig. 4 is a vertical sectional view on the line IV—IV of Fig. 1;

Fig. 5 is a sectional view showing a detail of this mechanism;

Fig. 6 is a diagram showing how the mechanism above referred to cooperates electrically with photographic apparatus proper.

In the following description, I will describe a photographic apparatus with a focal-plane shut-

ter, for aerial photography, this apparatus being intended to be automatically operated through the emission of electric current impulses.

According to the essential feature of the present invention, I use, for emitting the electric current impulse, a mechanism which is essentially constituted by the following elements:

a. A movable member adapted to be displaced, against the action of an elastic system, along a driving element which, in the following description, will be supposed to consist of a screw;

b. Means, preferably adjustable in position, for disengaging at will said movable member from said endless screw when said movable member comes into contact with the above mentioned means in the course of its movement along said screw;

c. Means, operative by said movable member in the course of its return movement under the action of the elastic means for temporarily closing said electric circuit, and means for bringing back said endless screw into engagement with said movable member, whereby the above mentioned cycle of operation can be repeated once more.

Such a mechanism truly constitutes an automatic system of control for the apparatus, as long as a rotational movement is transmitted to the endless screw.

Preferably, the system will be devised in such manner that the duration of the impulse emitted by said mechanism is merely sufficient for making it possible to release the apparatus proper and the starting of the motor which is to ensure, among other operations, the movement of the film and the resetting of the shutter, said apparatus being arranged, as will be more explicitly explained in what follows, in such manner that the action of the motor lasts for the time necessary for carrying out the operation, which time may be, for instance, three seconds approximately, the duration of each impulse being, in this case, say approximately one second.

In order to obtain this result, it is advantageous to use the embodiment of Figs. 1 to 5, which will now be described in detail:

The essential parts of this mechanism are grouped on a support such as a plate 1 which is fixed on the aircraft close to the operator's hand, for instance on a wall 2. The whole of these parts is located behind said wall, advantageously inside a casing 3, whereas the control element or elements of the mechanism are arranged to project on the other side of the wall, that is to say 55 toward the operator.

Plate 1 supports a motor 4, either electric or not, which is supposed to turn in a continuous manner, said motor being preferably chosen with an excess of power, and being advantageously provided with a regulating brake 5 of the centrifugal type. For instance, as shown by Fig. 5, two shoes 6 are applied against a friction drum by the centrifugal force against the action of a spring 7.

This motor cooperates, through a speed reducing gear 8, 9 and a worm 10, with a rod 11, threaded at one of its ends in such manner as to constitute a screw, said rod being arranged at right angles to the axis of said motor and having its non-threaded end journalled in a support 12.

This screw serves to drive a movable device constituted, for instance, by a block 13 slidably mounted on a rod 14 but angularly fixed with respect thereto. This rod 14, which is capable of turning about its axis, carries an elastic system, such for instance as a coil spring 15 which urges the movable member toward the end of the screw 11.

Block 13 is provided, on the side thereof, with a finger 16 capable, according to the position of rod 14 about its axis, either of being held apart from screw 11, or, on the contrary, of engaging in the threads thereof. Preferably, these threads are of a longitudinal section analogous to the shape of saw teeth, so as to facilitate the engagement of finger 16 therewith in the direction of its forward movement against the action of spring 15.

Elastic means are provided for keeping rod 14 in either of the angular positions thereof corresponding respectively to the case in which finger 16 is driven by screw 11 and to the case in which said finger is held apart from said screw.

These means may, for instance, be made as follows:

Rod 14 carries an arm 17, fixed on the end thereof, and a snap action spring 18 is interposed between the end of said arm and the end 19' of a bell crank lever 19.

The other end 19'' of said lever carries an abutment 20 with which is adapted to cooperate a piece 21 rigid with the movable member 13, during the return stroke thereof, so as to produce a pivoting of lever 19 such that spring 18 comes into a position in which it tends to bring back finger 16 into contact with screw 11, this pivoting of lever 19 taking place against the action of a spring 22.

I provide means for releasing the movable member 13, at a movable point of its stroke, through a kind of inclined surface 23 capable of coacting with a lug 24 carried by block 13. This inclined surface is carried by a member capable of moving along screw 11, for instance under the action of a rack 25 coacting with a pinion 26 capable of being operated by means of a suitable member, such for instance as a knob 27 preferably movable along a dial indicating the impulse frequencies corresponding to different successive positions of inclined surface 23.

Finally, I provide, in the circuit through which the impulses intended to operate the photographic apparatus are to be sent, a circuit breaking device some elements of which are arranged across the return path of the movable device. This circuit breaking device is adapted to be normally open and the sliding member 13 is to close it temporarily, for a time which has been supposed, by way of example, to be about one second.

This circuit breaking device is, for instance, made as follows:

I employ an oscillating circuit breaker one of the blades 28 of which is secured to a fixed support 29 while the other blade 30 is fitted to the end of a pivoting piece 31 mounted on a spindle 32 and subjected to the action of a spring 33 which tends to move blades 28 and 30 away from each other.

Block 13 coacts with the other end of pivoting piece 31, the latter being arranged in such manner that, when said block occupies the angular position for which finger 16 is out of contact with screw 11, it can engage under the end in question, and then compel said end to move down during the swinging movement of rod 14 which brings back finger 16 into contact with said screw, the contact remaining established until block 13, which is then driven by screw 11, releases pivoting piece 31, which then comes back into circuit breaking position under the action of spring 33.

The mechanism above described permits of emitting, at an adjustable rate, a series of electrical impulses into the control circuit of the photographic apparatus.

I will now describe the operation of such a device:

It will be supposed that movable member 13 is in its position shown by Figs. 1 and 2, that is to say in a position for which finger 16 is in engagement with the end of screw 11. It will be readily understood that, under the driving action of said screw, said movable member 13 is displaced along rod 14, compressing spring 15 in the course of its movement.

When lug 24 comes into contact with inclined surface 23, the latter will produce the swinging movement of block 13 and finger 16 will be moved away from screw 11. Rod 14 and arm 17, which are angularly rigid with block 13, undergo the same swinging displacement and snap action spring 18, after having moved past its neutral position, keeps finger 16 in a position away from screw 11. Said block 13, on which the pressure of spring 15 is acting, then moves freely in the backward direction and comes to engage under the free end of pivoting piece 31.

Near the end of the movement of block 13, piece 21 coacts with abutment 20 for producing the swinging movement of lever 19 against the action of spring 22. This swinging movement will modify the direction of the snap action spring 18, which will bring back the whole of arm 17, rod 14, and block 13 into the angular position for which finger 16 is in mesh with the end of screw 11. In the course of the displacement of these parts, block 13 compels the end of pivoting piece 31 to move in a downward direction and blades 28 and 30 come into contact with each other, against the action of spring 33, which has the effect of permitting the flow of an electric current through the control circuit of the photographic apparatus. This current flows as long as pivoting piece 31 is subjected to the pressure exerted thereon by block 13. The latter, being again connected with screw 11, will resume its forward movement, piece 21, accordingly, will cease to push back abutment 20, and bell crank lever 19 will return to its initial position under the action of spring 22 (position in which the snap action spring 18 still keeps finger 16 in engagement with screw 11).

After a forward displacement of finger 16 corresponding to a few threads of screw 11, the end of swinging member 31 escapes from under said block and 78 the contact is broken.

The movable member will then keep moving until it comes back once more into contact with inclined surface 23. Then the same operations as above described will take place, and so on, the desired impulses being produced at the desired cadence.

In order to make it possible to adjust the time elapsing between two successive impulses, it is sufficient to displace inclined surface 23 by means of control knob 27, which varies the period of time for which the movable member is driven by screw 11.

The photographic apparatus proper can be made, as a whole, in any suitable conventional manner, and in particular, as described in the prior patents above referred to, in such manner that the electrical impulses in question are caused to act upon a clutch capable of temporarily coupling together the various parts to be driven and a motor rotating in a continuous manner.

According to another embodiment, which will now be described, means are provided for causing the electrical impulses periodically to close the feed circuit of an electric motor coupled in a permanent manner to the parts to be driven. This operation can be obtained in a particularly simple manner with the arrangement diagrammatically shown by Fig. 6. In this embodiment of the invention, contact 28, 30 is inserted in the energizing circuit e of an electro-magnet 34 the armature 35 of which, when it is attracted by said electro-magnet, closes a contact 36 inserted in series in the feed circuit E of a motor 37. Means, not shown in this figure, are further provided for causing the period for which circuit E is closed to be longer than the period of time for which circuit e is closed.

What I claim is:

1. In a photographic apparatus having an electric circuit to be periodically closed, the combination of a frame, an endless screw journaled in said frame, a motor for driving said screw, a shaft supported by said frame parallel to said screw, an element slidable along said shaft and pivotable about the axis thereof, adapted to engage said screw so as to be driven by it in one direction, means for elastically opposing the movement of said element along said shaft in

said direction, snap action means for bringing and keeping said element out of engagement with said screw, an inclined member, adjustably carried by said frame, adapted to cooperate with said element in the course of its forward stroke for bringing said snap action means into play, means, operative by said element, for temporarily closing said circuit, and means for bringing back said element into engagement with said screw at the end of said backward stroke.

2. Apparatus for controlling current impulses for control of a photographic apparatus, comprising circuit making and breaking means, a rotatably mounted rod, a member slidably and non-rotatably mounted on said rod, a threaded spindle parallel with said rod, a tooth on said member engageable with the threads of said spindle, means to rotate said spindle continuously at constant speed in one direction, whereby to move said member in one direction when the tooth is engaged with the spindle threads, means operated by movement of said member during one portion of its movement in such direction to operate said circuit making and breaking means, means to turn said rod and member to disengage the tooth from the spindle threads during a different portion of its movement in such direction, spring means to move said member in the opposite direction when so disengaged, and means operable at the end of the movement of said member in such opposite direction to turn the rod and member to reengage the tooth with the spindle threads, whereby to vary thereby the time between operations of said first means while preserving the length of each operation thereof constant.

3. In apparatus as claimed in claim 2, said first rod and member turning means comprising an inclined surface mounted in the path of said member for adjustment in a direction parallel to said rod and spindle.

4. In apparatus as claimed in claim 2, said circuit making and breaking means including a part located in the path of the member during its last turning movement and movable thereby to make the circuit, said member during its movement in said first direction moving out of engagement with said part to open the circuit.

ISAAC KITROSER.

CERTIFICATE OF CORRECTION.

Patent No. 2,331,916.

October 19, 1943.

ISAAC KITROSER.

It is hereby certified that error appears in the above numbered patent requiring correction as follows: In the drawings, Sheet 2, Figure 6 as shown below should appear as a part of the patent -

and that the said Letters Patent should be read with this correction therein that the same may conform to the record of the case in the Patent Office.
Signed and sealed this 15th day of January, A. D. 1946.
